UNITED STATES PATENT OFFICE.

ROBERT W. WIEDERWAX, OF ATLANTIC CITY, NEW JERSEY, ASSIGNOR TO GEIST MANUFACTURING COMPANY, OF ATLANTIC CITY, NEW JERSEY, A CORPORATION OF DELAWARE.

BURNER.

Application filed June 2, 1922. Serial No. 565,339.

To all whom it may concern:

Be it known that I, ROBERT W. WIEDERWAX, a citizen of the United States, residing at Atlantic City, in the county of Atlantic and State of New Jersey, have invented certain new and useful Improvements in Burners, of which the following is a specification.

This invention relates to burners, and more particularly to oil burners.

10 An object of the invention is the provision of an oil burner having separate retorts to preheat the oil and fluid employed to support combustion.

15 A further object is the provision of a pre-heater for heating the fluid employed to support combustion which preheater will materially expand air or produce live steam when a mixture of oil and steam is employed in the burner.

20 A further object is the provision of a burner in which oil vapor is delivered to the burner pipe at an angle to the flow of steam or vapor and is deflected by the walls of the pipe to thoroughly mix the air of steam with 25 the oil.

In the accompanying drawings, I have shown one embodiment of the invention. In this showing:

30 Figure 1 is a central vertical longitudinal sectional view,

Figure 2 is a transverse vertical sectional view on line 2-2 of Figure 1, and,

Figure 3 is a detail sectional view on line 3-3 of Figure 2.

35 Referring to the drawings, the reference numeral 1 designates a shell or tubular casing forming the body portion of the burner. This shell is provided with an open rear end 2 and is further provided with inclined walls 3 adjacent the front end forming a restricted outlet 4. A tubular member 5 is arranged around the rear portion of the casing slightly spaced therefrom, forming an oil retort 6. One end of this tubular member is

40 extended at an angle, as indicated at 7, and welded to the main casing, as at 8. The other end is provided with a flange 9. A similar tubular member 10 surrounds the forward portion of the casing and is spaced therefrom to form a preheater 11. This member is provided with a flange 12 at its rear end, spaced from the flange 9, and the adjacent ends of these members are adapted

45 to be welded to the casing by a filling 13 of

metal. The forward end of the main casing is provided with an offset portion 14, adapted to receive a flange 15 on the forward end of the tubular member 10 and this flange is welded to the casing, as indicated at 16. An oil delivery pipe 17 is connected to the retort 6, preferably at the bottom and the retort is provided with a discharge pipe 18. An inlet pipe 26 is connected to the preheater, and the preheater is further provided with an outlet pipe 27. The pipe 27 communicates with a valve casing 19, having a valve therein controlled by valve stem 20.

55 Referring to Figure 3 of the drawings, a burner pipe 21 is connected to the valve casing by means of a pipe 22 and a union 23. A jet 24 is arranged within the pipe 22 and projects into the burner pipe. This jet is welded in the rear end of the pipe 22, forming a plug 25 of metal which prevents the passage of air, gas, or vapor rearwardly into 60 the valve casing 19.

65 The pipe 18 is connected to a valve casing 28. The burner pipe 21 is provided with a branch 29, extending downwardly at an angle. This extension is connected to the valve casing 28 by a pipe 30 and a union 31. The forward end of the burner pipe is provided with a reduced outlet 32.

70 The operation of the device is as follows:

75 Oil is delivered to the retort 6 from the main pipe 17 and is vaporized by the heat generated from the burner. When the burner is employed with air, partially compressed air is delivered to the preheater 11 through the pipe 26. I have found that the air in the preheater is heated to such an extent that it expands in volume to about twice its original size and it is thence delivered to the burner pipe through the pipe 27. By preheating the air in this manner, the volume of the air delivered to the burner is materially reduced, which eliminates one of the greatest expenses in the operation of liquid fuel burners. Oil vapor entering the burner pipe through the pipe 29 travels at an acute angle to the flow of air through the jet 24 and strikes the wall of the burner pipe rearwardly of the forward end of this jet. The rear end of pipe 22 being closed by the plug 25, compels the vapor to travel forwardly through the burner pipe to the opening 32 and it is thus deflected when it strikes the wall of the burner pipe through this

pipe in a forward direction. This tends to thoroughly break up the particles of vapor and cause a substantially complete intermixing with the air. It further causes a 5 whirling motion of the oil vapor and air and this mixture is delivered from the burner pipe in a whirling motion and burned.

When steam is employed in place of compressed air, cold water may be admitted to 10 the preheater 11 from the pipe 26 and the heat within the preheater is sufficient to generate live steam which is delivered to the burner pipe in a manner similar to the compressed air. Heretofore, it has been necessary to employ live steam generated in a 15 separate source, such as an ordinary heating boiler which rendered the use of such burners impossible where a source of live steam was not available. By means of a burner 20 constructed in accordance with the disclosure of the present application, I may either heat air to such an extent that a great deal of the heretofore necessary compression of the air is eliminated, or may heat cold water and 25 generate live steam to be employed in the burner.

It is to be understood that the form of my invention herewith shown and described is 30 to be taken as a preferred example of the same, and that various changes in the shape, size, and arrangement of parts may be resorted to without departing from the spirit of the invention or the scope of the subjoined claims.

35 Having thus described my invention, I claim:

1. A burner for liquid fuel comprising a 40 burner casing, a burner pipe arranged in said casing, a retort surrounding said casing, a preheater for fluid surrounding said casing, and connections between said retort, said preheater and said burner pipe.

2. A burner for liquid fuel comprising a 45 casing, a burner pipe arranged in said casing, a tubular member surrounding said casing and spaced therefrom to form a retort, a second tubular member surrounding another portion of said casing and spaced therefrom to form a preheater for fluid to 50 be mixed with said fuel to support combus-

tion, a connection between said retort and said burner pipe, and a connection between said preheater and said burner pipe.

3. In a burner for liquid fuels, a casing 55 having open ends, a burner pipe arranged in said casing, a retort surrounding said casing, a preheater surrounding said casing for preheating fluid to be mixed with said fuel, and pipes connecting said retort and said preheater to said burner pipe. 60

4. In a burner for liquid fuels, means for heating the fuel, means for preheating a fluid to be mixed with said fuel, a burner pipe closed at its rear end, a jet extending through the rear end of said burner pipe 65 and terminating therein, said jet being connected to said fluid heating means, and an inlet pipe for vaporized fuel arranged at a rearwardly extending angle and communicating with said burner pipe adjacent the 70 outlet end of said jet.

5. In a burner for liquid fuels, means for heating the fuel, means for preheating a fluid to be mixed with said fuel, a burner pipe, a plug arranged in the rear of said 75 burner pipe and having a central opening, a jet extending through said opening and terminating intermediate the ends of the burner pipe, means for delivering said fluid to said jet, and an inlet pipe for fuel 80 communicating with said burner pipe adjacent the outlet end of said jet and arranged at an angle thereto to initially deliver said fuel into said burner pipe rearwardly around said jet. 85

6. A burner for liquid fuels comprising a substantially tubular burner casing having open ends, a retort surrounding the rear of said casing, a preheater surrounding said casing forwardly of said retort, a burner 90 pipe arranged adjacent the rear of said casing, a jet arranged in said burner pipe, a pipe connecting said jet to said preheater to deliver heated fluid to said jet, a branch pipe extending from said burner pipe intermediate the ends of said jet, and a pipe connecting said branch pipe to said retort. 95

In testimony whereof, I affix my signature.

ROBERT W. WIEDERWAX.
